UNITED STATES PATENT OFFICE.

CHARLES J. HOLUB, OF COLUMBUS, OHIO, ASSIGNEE OF ONE-THIRD TO W. C. LAMNECK
AND ONE-THIRD TO A. P. LAMNECK, BOTH OF COLUMBUS, OHIO.

PIPE CORRUGATING AND BENDING MACHINE.

Application filed July 13, 1921. Serial No. 484,449.

To all whom it may concern.:

Be it known that CHARLES J. HOLUB, a citizen of the United States, residing at Columbus, in the county of Franklin and State of Ohio, has invented certain new and useful Improvements in Pipe Corrugating and Bending Machines, of which the following is a specification.

This invention relates to an improved machine specifically adapted for the purpose of operating upon sheet metal to produce corrugated pipe sections or elbows of the type commonly employed in connection with stove, gas range or furnace fittings, the primary object of the invention being to provide a machine which will be capable of quickly and accurately completing such pipe sections so that a relatively large production thereof may be effected in a labor and time saving manner over machines hitherto employed for this purpose.

The invention consists in the provision of a machine capable of receiving suitable lengths of straight metal pipe sections and in the provision of automatically operating mechanism, including a plurality of radially movable plungers, adapted for the purpose of producing corrugations in said pipe sections, and to simultaneously bend the latter into the desired elbow formation, the mechanism provided in the machine being therefore capable of simultaneously corrugating, bending and locking the free edges of the pipe section so that a completed elbow may be produced by the machine during its normal cycle of operation.

Other objects of the invention reside in the provision of an improved machine of this character wherein is embodied novel mechanism in the nature of an intermittently movable carriage for directing the pipe sections into engagement with the corrugating mechanism, in the provision of automatic means for automatically starting and stopping the operation of the machine, in mechanism for properly bending the pipe sections through an arc of substantially 90° after the formation of said corrugations, the said latter means being further operable to compress the corrugations so formed in order that a neat, properly bent and well finished elbow will be produced and wherein the adjacent edges thereof will be locked against relative separation.

With these objects in view, among others,

the invention further consists in the novel features of construction, combinations of elements and arrangements of parts, herein-after to be fully described and pointed out in the claims hereunto appended.

In the accompanying drawings, forming a part of this specification, and in which similar characters of reference denote like and corresponding parts throughout the several views thereof:

Fig. 1 is a side elevation of the improved pipe bending and corrugating machine comprising the present invention,

Fig. 2 is a top plan view thereof,

Fig. 3 is a vertical longitudinal sectional view taken through the machine on the plane indicated by the line 3—3 of Fig. 2,

Fig. 4 is a vertical transverse sectional view taken along the line 4—4 of Fig. 1,

Fig. 5 is a similar view taken along the line 5—5 of Fig. 1,

Fig. 6 is an end elevation of the machine and disclosing more particularly the corrugating and bending mechanisms,

Fig. 7 is a fragmentary end elevation on a somewhat larger scale disclosing more fully one of the radially disposed units of the corrugating mechanism,

Fig. 8 is a sectional view taken through said corrugating mechanism on the line 8—8 of Fig. 7,

Fig. 9 is a transverse sectional view taken along the plane indicated by the line 9—9 of Fig. 7,

Fig. 10 is an enlarged vertical sectional view disclosing more particularly the mandrel, carriage and feeding mechanism of the machine, together with the bending arm construction,

Fig. 11 is a similar view disclosing the operation of the corrugating and bending mechanisms when operating upon a pipe section,

Fig. 17 is a side elevation of a hand tool for adjusting the eccentric gear of the corrugating dies.

Referring more particularly to the details of the invention and to the structural peculiarities of the specific embodiment thereof disclosed in the drawings, the numeral 10 designates my improved machine in its entirety. In the art of manufacturing sheet metal piping, considerable difficulty, waste and expense has hitherto been involved in producing corrugated elbows of the type employed in uniting relatively angularly extending pipe sections, of the type employed in conjunction with the flue outlets of various kinds of heating units. It has been customary heretofore to provide a machine whereby such pipe sections may be first corrugated, and then to take such corrugated sections and place the same in a bending machine for the purpose of giving the desired elbow contour thereto. The prior art has thus utilized two separate and distinct machines, while the present invention provides but a single machine capable of producing the functions hitherto effected by the specified plurality of the machines, the construction 30 of the machine 1 being such that the operation of producing elbow sections may be expeditiously and simply carried out in the labor saving and economical manner, at the same time to produce a finished product which will be marked by its superiority, both in finish, strength and general efficiency over the pipe sections produced by machines heretofore employed for this general purpose.

40 The machine 1 is formed to include a bed 2, which may be supported by means of vertical legs 3. The upper surface of the bed is provided at one end with spaced bearings 4 and 5, which act to rotatably receive a power shaft 6. The latter in this instance has its outer end equipped with a belt wheel 7 by means of which power may be suitably delivered to the machine to rotate the shaft 6. A spur pinion 8 is mounted upon the 50 shaft 6 to rotate therewith, and this pinion is adapted to mesh with a relatively enlarged gear 9, loosely mounted for rotation about a horizontally extending countershaft 10. This shaft is mounted for rotation within the bearings 4 and 5 at a position above the power shaft 6.

60 Arising vertically from the bed 2 and disposed adjacent to the bearing 5, is a vertical frame wall 11, which has the corners thereof provided with suitable bearings capable of receiving the inner ends of a plurality of longitudinally extending shafts 12, the latter having their outer ends also suitably journaled within bearings 13 provided in an outer frame wall 14. The inner ends of the

shafts 12 are provided with fixed spur gears 15, which mesh with a centrally disposed drive gear 16, the latter being fixed to rotate with the counter shaft 10. It will be apparent, therefore, that upon the rotation 70 of said countershaft motion will be imparted to the gear 16 and thence to the meshing gears 15, which, in turn, operate to effect rotation on the part of the longitudinally extending shafts 12.

75 As before stated the gear 9 is loosely mounted upon the countershaft, hence use is made of an automatically operable clutch structure 17, which is adapted to connect the gear 9 with the countershaft 10, in order 80 that the latter may, at regulated periods, be rotated in unison with the power shaft 6.

To this end, the gear 9 is provided, contiguous to its hub, with a longitudinally extending bolt 18, the enlarged head 19 of 85 which being disposed to project to one side of the gear 9 so as to be capable of engaging with the clutch structure 17. As shown more particularly in Figures 14 and 15, the said clutch structure consists essentially of 90 a sleeve 20, which is slidably mounted upon the counter shaft 10 and is feathered as at 21 to said countershaft so as to be capable of rotating therewith. Formed in the sleeve 20 contiguous to the periphery thereof is a 95 longitudinally extending slot 22, in which is slidably mounted a retractile latch bar 23, the said bar being normally urged outwardly by means of a coil spring 24, which has its movement regulated by means of a lateral projection 25 formed upon said bar. Thus, when the bar 23 responds to the influence of its spring 24, the same will be projected outwardly or longitudinally until 100 its movement is curtailed by the engagement of the projection 25 with the annular flange 26 surrounding the sleeve. This locates the latch bar in the path of movement or rotation of the head 19, thus causing the 105 said sleeve, and consequently the counter-shaft 10 to rotate in unison with the power shaft, and the said countershaft in turn imparts rotation to the gears 15 and their respective shafts.

To control positions of the latch bar 23, the upper end of the bearing 5 has pivoted thereto as at 27 an arm 28 which is of substantially the shape of a bell crank lever. The outer end of this arm is articulately connected as at 29 with a link 30, the said 110 link having its outer end pivotally connected as at 31 with the lower end of a crank arm 32, which is fixed to one end of a clutch operating shaft 33. This shaft is suitably mounted in the inner and outer 115 frame walls 11 and 14, and extends parallel and longitudinally with the shafts 12. By mechanism to be hereinafter more fully described, the shaft 33 is capable of being 120 oscillated, so as to impact corresponding 130

movement to the crank arm 32, in order that the arm 28 and the link 30 may be raised or lowered toward and away from the bar 23. Connected with the members 28 and 30 contiguous to their connection 29 is a shoe 34, which is provided with a cam surface 35, the latter being adapted for cooperation with a similar surface 36 provided on the projection 25. Thus, when the shaft 33 is rotated so as to raise the shoe 34, it will be apparent that the latter will be engaged by the projection 25, and by reason of the cam surfaces 35 and 36, the latch bar 23 will be retracted against the influence exercised by its spring 24. The retraction of the latch bar of course results in breaking the driving relation which exists between said latch bar, when the latter is projected, and the head of the bolt 18, a feature which results in stopping the rotation of the countershaft 10. The rotation of the sleeve 20 is positively arrested when the connection between the bar 23 and the bolt 18 is removed, by employing an adjustable friction band 37. This band is pivotally mounted in connection with the upper end of the bearing 5, and is provided with relatively spaced jaws 38, which are capable of receiving a screw 39 carrying a wing nut 40. Manifestly, by adjusting the nut 40, the friction which the band 37 is capable of exercising upon the periphery of the sleeve may be readily regulated. Therefore, by this construction it will be apparent that when the shoe 34 is elevated, the same will be projected into the path of movement of the projection 25, and when the surfaces 35 and 36 have been fully engaged, the latch bar 23 will be retracted to break the driving relationship between the gear 9 and the sleeve 20. The momentum of the sleeve, gained by its rotation in unison with the gear 9, is overcome by the band 37, which operates to stop movement on the part of the sleeve while the projection 25 is yet in engagement with the shoe 34, a feature which insures a positive retention of the latch bar. Conversely, when the clutch shaft 33 is operated to lower the shoe 34, the latter is moved out of engagement with the projection 25, thus causing the bar 23 to be projected by its spring 24 into engagement with the head 19. The arm 28 is provided with an offset end 41, to which a coil spring 42 is attached. This spring has its outer end connected with the frame of the machine and therefore the normal tendency of the spring 42 will be to rotate the arm 28, so as to effect elevation on the part of the shoe 34. This tendency, however, on the part of the spring 42 is subject to the regulation exercised thereon by the clutch shaft 33, as will be hereinafter more fully explained. It will of course be appreciated that the band 37 may be provided with a wear receiving lining 43, which

may be removed or replaced whenever desired.

The inner frame wall 11 is formed to include a pair of spaced apertured lugs 44, which are adapted to receive between them the upstanding ears 45 provided upon a metallic band 46, the latter serving as a pivoted bearing to receive the inner end of a longitudinally extending mandrel or core 47. It will be observed that the mandrel 47 is situated in axial alignment substantially with the countershaft 10 and is adapted to have its outer end received within an opening 48 provided in the outer frame wall 14. By means of the set screw adjustment 49, which is carried by the band 46 and cooperates with the wall 11, the said mandrel may be adjusted about its pivotal support 44 and 45, so that the outer end thereof may be properly maintained in any desired position of axial adjustment. It will of course be understood that a cross pin 50 will pass through the apertures formed in the lugs 44 and 45 so that the mandrel as a whole may be pivotally supported by means of the inner frame wall 11. Provided in the periphery of the mandrel 47 is a longitudinally extending slot 51. This slot is arranged to slidably receive a ratchet bar 52, carrying ratchet teeth 53 along its upper edge. Arranged to move longitudinally of the mandrel 47 is a slidable carriage 54. This carriage may be formed to include a collar 55, which is suitably slotted to receive the bar 52. The top of the collar is provided with a bracket 56, to which is pivoted a lever 57. One end of this lever pivotally carries a downwardly extending stud 58, which passes through an opening provided in the collar and is capable of entering an annular open ended chamber or socket 59 formed in one end of the collar 55. As shown more particularly in Figure 10, this socket is disposed concentrically of the mandrel 47 and is capable of registering with the opening 48 provided in the outer frame wall 14, when the carriage is moved to its extreme outer position upon the mandrel. By locating the socket 59 in the position disclosed, the same will be capable of receiving one end of a straight metallic pipe section 60.

To hold the pipe section 60 in connection with the collar the lever 57 is pivotally connected as at 61 with an upstanding lever 62, the latter being provided at its lower end with a cam surface 63 capable of engaging with a similar surface 64 provided upon the collar 55. The lever 62 is also provided with a spring 65 which terminates at its lower end in an offset shoulder 66, the latter being disposed for engagement with a similar shoulder provided upon the upper end of a latch pin 67. This pin is mounted for vertical movement within an opening 68

provided in the collar, and the lower end thereof is adapted for engagement with the teeth of the ratchet bar 52, a spring 69 being utilized to normally maintain the lower end of said pin in engagement with said teeth. By this construction it will be apparent that when the collar 55 is positioned at the extreme outer end of the mandrel, one end of the pipe section 60 may be inserted within the socket 59. Then, by oscillating the upstanding lever 62, the stud 58 will be pressed into engagement with the end of the pipe section within the socket 59, thereby positively retaining said pipe section in connection with the collar, the cam surfaces 63 and 64 serving to effectively retain the lever 62 in its adjusted position. Simultaneously with the clamping of the pipe section, the latch pin 67 is elevated, against the tension of its spring 69, from engagement with the ratchet teeth 53, thus freeing the collar from locked engagement with the ratchet bar, so that the collar or carriage may be shifted inwardly and longitudinally of the mandrel 47 carrying the pipe section in unison therewith.

When the carriage has been moved by a manual operation to its extreme inward position, the spring latch 65 is engaged by the outer end of a fixed pin 70, which projects longitudinally from the inner frame wall 11. This forces the said spring latch 65 out of engagement with the pin 67, so that the latch pin 67 is released from engagement therewith, thus allowing the pin 67 to respond to the action of its spring 69 so that the lower end thereof may be forced into engagement with the vertical walls of the ratchet teeth 53, as is clearly shown in Figure 10. When the latch pin is thus lowered, the clutch structure 17 is automatically operated so as to effect reciprocation on the part of the bar 52, in order that the carriage will be intermittently fed longitudinally of the mandrel in an outward direction, so that the pipe section carried by the carriage may be subjected to the action of the corrugating mechanism hereinafter to be fully described. To automatically operate the clutch structure, the collar 55 is provided with a laterally extending fixed lug 71, in which is mounted a longitudinally extending, adjustable set screw 72. This screw is so positioned that the same will be enabled to enter a bifurcated lug 73 projecting from the wall 11. Slidably mounted between the walls of the lug 73 and a similar lug 74 provided upon the outer wall, is a sliding frame 75, which extends parallel with the mandrel 47, and includes a longitudinally disposed bar 76 and vertically disposed heads 77, the latter being slidably received between the walls of the lugs 73 and 74. The head 77 adjacent to the inner wall 11 is arranged to be engaged by the end of the set screw 72, in or-

der that when the carriage reaches its extreme inward position, the frame 75 will be reciprocated. The lower portion of the head 77, situated near the wall 11, is provided with a cam surface, which is capable of engaging with a similar cam surface provided upon a fixed crank 78, which is carried by the clutch shaft 33. Manifestly, the engagement of the set screw 72 with the head 77 will result in oscillating the upper end 75 of the crank 78 outwardly, thus causing partial rotation on the part of the clutch shaft 33, which in turn serves to operate the members 28 and 30, so that the shoe 34 will be moved to a position permitting of the projection of the latch bar 23, thus insuring rotation of the countershaft 10, and consequently the rotation of the intermediate gear 16 and the outer gears 15.

The intermediate gear as shown in Figure 16, is provided with an adjustable cam member 79, capable of being retained in various circumferentially adjusted positions by means of screws 80. The cam member 79 has its substantially V-shaped operating projection so positioned as to engage with the inner beveled end of the ratchet bar 52, which latter projects through an opening 81 provided in the inner wall 11. It will be observed that the outer end of the ratchet bar includes a depending projection 82, which operates in a slot 83 provided in the mandrel 47, and a spring 84 is situated to engage with the said projection so that the ratchet bar will be normally forced in an inward direction toward the gear 16. Manifestly, upon each complete rotation on the part of the gear 16, the cam member 79 carried thereby will engage with the inner end of the ratchet bar so that the latter will be forced outwardly and longitudinally against the resistance offered by the spring 84, and that after engagement between the ratchet bar and the cam member 79 has been broken, the said spring 84 will operate to return the ratchet bar to its normal position. This reciprocation on the part of the ratchet bar results in causing the carriage 54 to be intermittently advanced longitudinally of the mandrel, since the pin 67 will cooperate with said ratchet bar in a manner admitting of this function. It will also be observed that the collar 55 is connected with the upper end of a chain 85, which passes over a fixed sprocket 86, and has its lower end connected with a weight 87, the latter being disposed for operation within a rigid tube 88, depending from the bed 2. By the provision of the weight 87, it will be apparent that when the lever 62 is operated to release the pin 67 from engagement with the ratchet bar, the collar or carriage will be automatically moved inwardly and longitudinally of the mandrel by the action of the weight, thus rendering

the machine manually convenient to operate. Outward movement on the part of the collar is of course effected by the automatic power driven mechanism previously described. 5 Moreover, by the provision of the sliding frame 75, engagement will be maintained between the lower end of the inner head thereof and the crank 78, a feature which results in maintaining the clutch structure in 10 a position establishing driving relationship between the countershaft 10 and the intermediate gear 16, thus causing power to be directly applied to the ratchet bar 52 until the said carriage reaches its extreme outer 15 position. When this position is reached, a set screw 89 carried by the arm or lock 71, engages with the outer head of the frame 75, thus releasing the crank 78, and permitting the clutch structure to return to its 20 normal inoperative position by reason of the influence exercised by the spring 42. This construction, therefore, admits of an automatic starting of the carriage in its outward movement and also of a similar 25 stopping of the carriage when the same reaches its extreme position of outward movement.

The corrugating mechanism embodied in the machine 1 has been specifically illustrated in Figures 6 to 9 inclusive, and in this particular form of the invention, it will be observed that the outer ends of the longitudinally extending shafts 12 upon which the gears 15 are mounted, terminate in sockets 90 provided in the outer frame wall 14 of the machine. The outer ends of the shafts 12 are of reduced polygonal formation and are adapted to be received within pockets 91 provided in collars 92 which are rotatably 30 journaled in the sockets 90. The outer ends of the collars 92 are provided with crank pins or eccentrics 93 of relatively reduced construction, which are adapted to receive surrounding bushings 94, the latter being 35 positioned within openings provided therefor in radially disposed eccentric straps 95. These straps are situated so as to lie in radial positions with respect to the axis of the mandrel 47, and are provided with split 40 ends 96 capable of being united by means of screws 97. By tightening the latter, the bushings 94 will be tightly held within the said straps, so that upon the rotation of the shafts 12 reciprocatory radial movement will 45 be imparted to the straps 95 by the action of the eccentrics 93. The inner ends of the straps 95 terminate in substantially circular heads 98, which are arranged to be received 50 within sockets 99 provided in sliding cross heads 100. These cross heads are arranged for radial movement within fixed guides 101, carried by the outer frame wall 14. The cross heads are fitted with removable plates 102, which operate to retain the heads 98 55 within the sockets 99. Also, the eccentrics 60

93 are equipped with removable cap plates 103, which serve to retain the bushings 94 against accidental displacement. It will be observed that the bushings 94 have their peripheries provided with gear teeth 104, 70 and that the straps 95 are equipped with openings 105. By this construction a suitable tool may be inserted within the openings 105 for engagement with the gear teeth 104, whereby the bushings may be rotatably adjusted so that the cross heads 100 may have their operative positions adjusted relatively to the longitudinal axis of the machine. Preferably, the guides 101 are of dovetail 75 construction in order to effectively retain 80 the cross heads therein.

The inner edges of the cross heads 100 are provided with recesses 106, in which are positioned and secured by means of screws 107, corrugating dies 108. These dies are of 85 segmental formation and are formed to include relatively reduced inner corrugating edges 109, each of which being approximately 90° curvature. The adjacent edges of the dies are formed to include lap joints 90 110, which serve to maintain proper registration between the dies in all of their various radial positions. The outer end of the mandrel 47, where it projects through the opening 48, is provided with a removable forming head 111, suitably provided with an annular recess 112, where it registers with the edges 109 of the corrugating dies. In 95 operation the pipe section 60 is slipped over the mandrel and connected with the carriage as previously described, the forming head 111 being of a diameter to correspond substantially with the inner diameter of the pipe section. Accordingly, the head 111 is 100 removably connected with the outer end of the mandrel in order that the machine may be adapted to pipe sections of varying diameter. The extreme outer end of the pipe section, before the latter is inserted into the machine, is provided with a removable cam ring 113, 105 which ring is formed to include an annular chamber 114, into which the outer end of the pipe section is inserted or positioned, the width of the cam ring being such that when the carriage has been moved to its extreme 110 inner position, the inner edge of the cam ring will be positioned contiguous to the forming head 111, but free from conflict with the radially moving reciprocal dies 108. Therefore, it will be apparent that when the clutch 115 structure 17 has been actively operated by the inward movement of the carriage, radial reciprocating movement will be imparted to the dies 108, thus forcing the latter into engagement with the longitudinally traveling pipe section, and the extent of movement of such dies is such as to produce the desired annular corrugations within the pipe section, and these corrugations are successively 120 formed by the intermittent outward move- 125 130

ment of the carriage. It will be appreciated that the timing of the machine is such that the pipe section will be moved longitudinally when the dies are moving outwardly, and that the pipe section will be at rest when the dies are producing corrugations therein. It will be observed that by the radial positions of the dies, the same when moved outwardly will permit of the convenient passage of the pipe sections therethrough, and that when said dies are forced inwardly the same will operate to produce the desired circular grooves in the pipe sections, which will be smooth, uniform and accurately finished and perfectly annular in formation.

Immediately following the corrugating operation, mechanism has been provided for automatically bending the said pipe sections through an arc of substantially 90° so that corrugated pipe elbows of desired physical characteristics may be produced. To this end the bed 2 is provided with spaced brackets 115, which operate to rotatably receive a shaft 116. This shaft is formed to include a pair of spaced upwardly extending bending arms 117, which are spaced apart a sufficient distance to permit of the passage of the cam ring or collar 113 therebetween, the extreme upper ends of said arms being provided with removable hardened steel, offset walls 118, which are so situated as to engage, as shown in Figure 11, with cam wings 119 provided on the ring 113. Manifestly, as the pipe sections are fed outwardly by the machine and corrugated through the instrumentality of the dies 108, the cam wings of the collar 113, carried by the outer ends of the pipe sections, will engage with the walls 118 of the arms 117 so that the pipe sections will be bent or curved to assume the construction particularly disclosed in Figure 11.

In order that the corrugations may be tightly forced together so that the pipe section may be bent or curved in the shortest possible radii, the shaft 116 includes a recessed depression 120, in which is positioned the free end of the pivoted pawl 121, the latter being pivotally mounted as at 122 within the bifurcated upper end of a throw arm 123. This arm carries an offset bracket 124 between which and the outer crank end of the pawl 121 a spring 125 is confined, the said spring normally operating to maintain the pawl in contact with the depression 120. It will be manifest that the arm 123 is loosely mounted upon the shaft 116, and that the arms 117 are fixed to said shaft. Wherefore, by the oscillation of the arm 123, the said pawl will serve to partially rotate the shaft 116 and thus to impart movement to the upper ends of the arms 117. This movement causes the offset portions 118 of said arms to engage with the wings 119 provided

upon the cam ring 113, thus delivering successive blows to the said cam ring immediately following the formation of each corrugation in the pipe section, a feature which results in properly bending said pipe sections within short compass and also in locking the free edges thereof against separation.

Many different constructions may be used for oscillating the arm 123. For instance, as shown in Figure 3 particularly one of the shafts 12 is formed to include a fixed cam 126. This cam is disposed for engagement with the free upper end of a lever 127, the latter being pivoted as at 128 to the under part of the bed 2, the lower end of said lever is disposed for engagement with a sliding plunger 129, which is horizontally reciprocated in a bearing 130 provided in conjunction with the bed 2. The outer end of the plunger engages with an adjustable screw 131 mounted and secured within the lower end of the arm 123, and a spring 132 operates to maintain engagement between the end of the screw 131 and the outer end of the plunger 129. Manifestly, the cam 126 may be so positioned that its effective surface will be brought into engagement with the lever 127 at timed intervals, which may be so regulated as to oscillate the arm 123 and the associated arms 117 immediately following the formation of each corrugation within a pipe section.

The clutch shaft 33 extends through and beyond the outer frame wall 14, and is equipped with a finger 133. This finger is capable of engaging at timed intervals with a laterally extending projection or bar 134 carried by the outer end of the pawl 121. Thus, when the collar or carriage has moved to its extreme outer position by the action of its feeding mechanism, the sliding frame 75 will be operated to throw the clutch structure to its inactive position. This results in oscillation on the part of the clutch shaft by reason of its response to the influence of the spring 42. This movement results in causing downward movement of the finger 133, which by engaging with the projection 134, raises or lifts the inner end of the pawl 121 out of the depression 120, thereby allowing the arms 117 to gravitate automatically to a lowered position, so that facility may be obtained in effecting the final removal of the completed pipe section. Similarly, the arms are automatically elevated after a pipe section has been properly inserted in the machine. This may be accomplished by providing the frame walls with a longitudinally extending rod 135, which carries a slidably mounted sleeve 136, the latter being formed with an offset projection 137, the outer end of which carrying a set screw 138, capable of engaging with

the collar 55, when the latter has been moved to its extreme inward position. The sleeve 136 carries a lateral extension 139, to which is pivotally connected a link 140, the 5 said link extending rearwardly and is connected as at 141 with the upper end of a crank arm 142, fixed to the outer end of the shaft 116. Therefore, by reason of this construction, when the pipe section has been 10 properly inserted into the machine, the arms 117 will be automatically elevated for engagement with the cam ring of the pipe section and to effect a bending or curving of said section in the manner disclosed.

15 In view of the foregoing description, taken in conjunction with the accompanying drawings, it will be apparent that the present invention provides a machine which will be capable of efficiently, easily and 20 rapidly producing in comparatively large numbers corrugated and curved metallic pipe sections, or flue elbows as the case may be. The machine has been formed to include various adjustments, whereby the 25 same may be adapted to accommodate various sized pipe sections, and thus to enable the machine to produce pipe sections of all standard diameters. This feature is insured by the ease with which the collar 55 may be 30 replaced, the adjustment afforded by the bushings 94 for regulating the radial operating positions of the dies 108, and the movable head 98. By these three adjustments the machine may be readily adapted 35 to a pipe section of any desired diameter. The dies 108 are also removably connected with the cross heads 100, a feature which enables the said dies to be readily replaced or repaired when worn or broken. The 40 radially movable dies operate to produce uniform corrugations within the pipe sections, and the action of the arms 117 serves to properly bend the said pipe sections, to compress the corrugations produced by the 45 dies, and to lock the free edges of the pipe sections together. It will be apparent that in removing or inserting a pipe section from or within the machine, the arms 117 will automatically assume a lowered position 50 which will render the end of the machine readily accessible.

I have illustrated in the drawings and described herein the construction which at the present time seems a preferable embodiment of my invention, but I do not limit myself to the construction shown and described but desire the benefit of all variations of construction and modifications thereof which express the spirit of my invention.

What is claimed is:

1. In a pipe forming machine, a frame, a longitudinally movable carrier mounted in connection with said frame and capable 65 of receiving the end of a metallic pipe sec-

tion, means operating to intermittently advance said carrier and the pipe section carried thereby longitudinally of said frame, a plurality of pipe corrugating members arranged circumferentially upon said frame 70 about said pipe section and mounted in fixed guides upon said frame to move radially relative to said pipe section, separate power driven shafts to actuate said respective corrugating members, each provided with a 75 crank pin, an eccentric sleeve rotatably mounted upon said crank pin, and a pitman connected to the corrugating member at one end and releasably clamped upon its eccentric sleeve at the opposite end, whereby 80 each corrugating member is readily independently radially adjustable to provide for corrugating pipe sections of different diameters upon the same machine.

2. In a pipe forming machine, a frame including spaced vertically situated inner and outer walls, a core carried by said inner wall and having the outer end thereof arranged to project through an opening provided in the outer wall, a carrier interchangeable with other carriers of different external diameter detachably mounted upon said core for intermittent longitudinal movement thereon, means carried by said carrier to detachably connect a pipe section thereto 90 to feed the pipe section with said carrier longitudinally of said core, an annular former member interchangeable with other former members of different external diameter 95 stationarily mounted upon said core at a position where corrugations are to be formed in the pipe section, a plurality of circumferentially arranged and radially movable power driven corrugating dies, separate driving shafts for said respective corrugating dies, and means to independently adjust said corrugating dies to and from said core to provide for interchangeably producing pipe elbows of different diameter upon the same machine.

3. In a pipe forming machine, a frame including spaced vertically situated inner and outer walls, a core carried by said inner wall and having the outer end thereof arranged to project through an opening provided in the outer wall, a carrier interchangeable with other carriers of different external diameter detachably mounted upon said core for intermittent longitudinal movement thereon, means carried by said carrier to detachably connect a pipe section thereto 100 to feed the pipe section with said carrier longitudinally of said core, an annular former member interchangeable with other former members of different external diameter 105 stationarily mounted upon said core at a position where corrugations are to be formed in the pipe section, a plurality of circumferentially arranged and radially movable power driven corrugating dies, having their ad- 110

jacent ends overlapping one another, separate driving shafts for said respective corrugating dies, and means to independently adjust said corrugating dies to and from said core to provide for interchangeably producing pipe elbows of different diameter upon the same machine.

4. In a pipe forming machine, a frame including spaced vertically situated inner and outer walls, a core carried by said inner wall and having the outer end thereof arranged to project through an opening provided in the outer wall, a carrier interchangeable with other carriers of different external diameter detachably mounted upon said core for intermittent longitudinal movement thereon, means carried by said carrier to detachably connect a pipe section thereto to feed the pipe section with said carrier longitudinally of said core, an annular former

member interchangeable with other former members of different external diameter stationarily mounted upon said core at a position where corrugations are to be formed in the pipe section, a plurality of circumferentially arranged and radially movable power driven corrugating dies, separate driving shafts for said respective dies, each provided with a crank pin, an eccentric sleeve rotatably mounted upon said crank pin and adjustably clamped in one end of a pitman, the other end of which pitman is connected to said corrugating die to provide for independently adjusting said corrugating dies to and from said core to enable pipe elbows of different diameter to be produced upon the same machine.

In testimony whereof I affix my signature.

CHARLES J. HOLUB.
